CONVERSION OF HYDROCARBONS

Richard F. Trow, Tuckahoe, N. Y., assignor to
The Texas Company, New York, N. Y., a corporation of Delaware

Application June 30, 1938, Serial No. 216,650

5 Claims. (Cl. 196—49)

This invention relates to a process for the conversion of hydrocarbon oils to gasoline of high anti-knock value.

It is an object of the invention to provide a process for effecting cracking of a relatively clean distillate oil under elevated conditions of temperature and pressure to effect conversion thereof to gasoline constituents of high anti-knock value and simultaneously effecting the viscosity breaking of a heavy oil in a manner whereby such viscosity breaking assists in preventing excessive coke deposition in the cracking of the distillate oil, effects intermediate removal of residual constituents formed in the cracking of the distillate oil and effects intermediate addition of preheated cracking stock to the distillate oil undergoing cracking. It is another object of the invention to provide a process of the above nature which is cyclic in operation and involves such novel operating improvements as will be found to pertain thereto from the following description.

According to the present invention a clean distillate oil such as a gas oil is subjected to cracking by the passage thereof as a stream through an elongated heating zone of restricted cross section such as a heated pipe coil, under elevated conditions of temperature and pressure. After substantial cracking has been effected the stream of oil undergoing conversion is commingled with a hydrocarbon oil having a higher boiling range than the said gas oil. This heavy oil may be a distillate oil such as a heavy gas oil or may be a residual oil such as topped or reduced crude. The resulting mixture is maintained under cracking conditions of temperature and pressure for a time sufficient to effect viscosity breaking of the heavy oil, and the resulting products are separated by passage of the stream through a zone of enlarged cross section, at a velocity substantially lower than the velocity of the stream in passing through the pipe coil, into a vapor fraction which includes constituents boiling above the gasoline boiling range and a liquid residue fraction. The vapor and liquid components of the stream are separately withdrawn from the zone of enlarged cross section, which may be a separator connected to the pipe coil, and the vapor component is passed as a stream through a second pipe coil wherein it is subjected to further cracking under elevated conditions of temperature and pressure. The admixture of the heavy oil with the stream may be effected by introducing the heavy oil into the first pipe coil at a plurality of points after which, after a suitable interval,

the mixed stream may be passed through the separator to effect the desired separation of vapors and liquid residue; or the heavy oil may be admixed with the stream undergoing cracking in the separator whereby the desired viscosity breaking is effected in the separator. The volatile products of the viscosity-breaking operation and of the cracking of the gas oil are withdrawn from the separator as a vaporous stream and the residue from both cracking operations, including residual constituents introduced into the separator with the heavy oil, is withdrawn therefrom separately.

The pressure maintained in the separator may be substantially the same as or lower than that maintained in the first pipe coil, and the pressure maintained in the second pipe coil may be substantially the same or lower than that maintained in the separator. Preferably, unnecessary reduction of pressure is avoided.

The accompanying drawing is a diagrammatic view in elevation of apparatus suitable for carrying out the process of the present invention. The invention will be further described in detail by reference to the drawing. It will be understood, however, that the drawing and accompanying specific description are merely illustrative of the invention which is capable of other modifications and embodiments than those illustrated and described.

In the drawing the cracking of the distillate oil is effected in heater 1, which is provided with a cracking coil 2 divided into two sections, 2a and 2b, which are connected through intermediate separator 3. The drawing illustrates diagrammatically a furnace of the type wherein a pipe coil is arranged in a plurality of sections about the wall of a furnace chamber which is circular in horizontal cross section. Such furnaces are ordinarily centrally fired whereby all parts of the coil thus arranged are equidistant from the zone of combustion or source of radiant heat. It is to be understood, however, that the two elongated cracking zones of restricted cross section employed in the present invention may be embodied by a pair of coils located in different parts of any conventional type cracking furnace; or they may be similar or different coils located in separate furnaces. For simplicity of illustration, however, a furnace of the first-mentioned type is illustrated.

In addition to the furnace and intermediate separator the apparatus is provided with a final separator 4, fractionator 5, receiver 6 and stabilizer 66. Suitable pipe connections are provided

- as shown for effecting transfer of the materials under treatment to and from the various treating zones.
- 5 In the operation of the process as illustrated in the drawing the clean distillate oil, which may be a gas oil, is introduced into section 2a of pipe coil 2 through line 10 which is provided with a pump 11 for maintaining the desired pressure in the pipe coil 2. The gas oil thus charged may consist entirely of fresh feed introduced from an external source or may include recycle stock. In section 2a of the pipe coil the gas oil passed therethrough is heated under appropriate conditions of temperature and pressure to effect substantial cracking thereof. For example, in section 2a of the pipe coil the stream passing therethrough may be heated to a temperature of the order of 900° F.-1000° F. under a pressure of 200-600 pounds per square inch.
- 10 According to one embodiment of the invention a heavy oil, which may be a residual oil such as reduced crude, is introduced into section 2a of the pipe coil at an intermediate point thereof through line 12 which is provided with a pump 13. This heavy oil is suitably preheated prior to introduction into section 2a of the pipe coil and, for example, in the case of reduced crude may be preheated to a temperature of 500° F.-700° F. It may be advantageous to heat the heavy oil to 15 higher temperatures, for example, temperatures as high as 825° F. to effect cracking prior to introduction into coil 2a. The temperature of the heavy oil thus introduced and the ratio of heavy oil to clean distillate undergoing cracking are regulated to produce the desired temperature conditions in the remaining portion of section 2a of the pipe coil 2. This temperature is preferably regulated to effect viscosity breaking of the heavy oil thus introduced with additional cracking of the clean distillate, as desired. The point of introduction of the heavy oil between the entrance and exit of section 2a of the pipe coil 2 is chosen with respect to the degree of cracking being effected on the clean distillate oil in the first part of section 2a of the pipe coil and the temperature to which the heavy oil is preheated whereby the heavy oil is admixed with the stream undergoing cracking before excessive coke formation occurs. The resulting mixture is thereafter withdrawn from section 2a through line 14, before excessive cracking of the tarry constituents of the mixture is effected, and introduced into intermediate separator 3 wherein separation of vapors and liquid residue is effected. Intermediate separator 3 preferably is maintained without reduction in temperature substantially below the cracking temperature. Suitable insulation may be provided for this purpose. Preferably also no unnecessary reduction in pressure is permitted in the passage of the cracked products from section 2a of the pipe coil to separator 3 although if desired positive reduction in pressure may be effected by means of valve 15 in line 14.
- 20 In separator 3 conditions of temperature and pressure are maintained to effect separation only of relatively high boiling residual constituents and the passage overhead of a vapor fraction which contains substantially all constituents suitable for further cracking treatment. The liquid residue separated in separator 3 is withdrawn therefrom through line 16 provided with pressure control valve 49 through which it may be passed to a vacuum tower 50 wherein a clean distillate such as a heavy gas oil is separated
- 25 from a heavy residue, which may be a high melting point pitch. The heavy residue is withdrawn from tower 50 through line 51. The vapors separated are withdrawn overhead through line 52 and cooler 53 whereby condensation of liquids is effected. The cooled mixture of vapors and uncondensed gases is separated in separator 54, and the gases are withdrawn therefrom through line 55 which contains pump 56 for maintaining the vacuum. The gas oil separated in separator 54 is withdrawn therefrom through line 57 which is provided with pump 58 and connects with line 38 whereby the gas oil thus separated is introduced into the upper portion of separator 4 and reprocessed.
- 30 In order to permit proper scrubbing of the vapors in separator 3 it is desirable to cool part of the residue therefrom and reflux the same over baffles in the top of separator 3. To this end a portion of the residual oil withdrawn from separator 3 through line 16 may be diverted therefrom through line 75 which is provided with a cooler 76, a pump 77 and connects with line 19 whereby a portion of the residual oil is cooled and introduced into the upper portion of separator 3.
- 35 The vapor fraction separated in separator 3 is withdrawn therefrom through line 17 which connects with the inlet of section 2b of pipe coil 2. This mixture of cracked products with in and above the gasoline boiling range, including uncracked gas oil introduced through line 10, distillate from the heavy oil introduced through line 12 and products of the viscosity breaking of the heavy oil, is subjected in section 2b to suitable conditions of temperature and pressure to effect conversion thereof to gasoline constituents of high anti-knock value. Preferably the pressure is not unnecessarily lower than that existing in separator 3. For example, the vapors passing through section 2b may be heated to a temperature of the order of 900° F.-1000° F. under a pressure of 200-600 pounds per square inch. If desired, however, any suitable reduction in pressure may be effected between separator 3 and section 2b of the pipe coil by means of valve 18 in line 17.
- 40 According to another modification of the invention the products of cracking of the distillate oil in section 2a of the pipe coil may be withdrawn therefrom through line 14 prior to admixture therewith of any heavy oil and prior to excessive coke formation. The products of conversion are introduced into separator 3 through line 14 as described and therein are contacted with a heavy oil introduced into separator 3 through line 19 provided with pump 20. This heavy oil, which may be a topped or reduced crude or heavy gas oil, is preferably preheated, for example to a cracking temperature. In separator 3 the products of cracking introduced through line 14 and the heavy oil introduced through line 19 are intimately admixed whereby cracking and viscosity breaking of the heavy oil are effected together with simultaneous separation of the products of the cracking operations and the distillation of the heavy oil into a vapor fraction and a liquid residue. The residue formed is withdrawn through line 16 and the resulting vapor fraction passed through line 17 for further cracking treatment in section 2b of the pipe coil, as described.
- 45 The stream undergoing conversion is withdrawn from section 2b of the pipe coil 2 through line 21 which connects the outlet of section 2b

to a final separator 4. If desired the products of cracking may be cooled by suitable means prior to introduction into separator 4, and any desired reduction in pressure may be effected by means of valve 22 located in line 21.

In separator 4 conditions of temperature and pressure are maintained to effect separation of a heavy residue which is withdrawn through line 23 and the passage overhead of a vapor fraction including constituents suitable for recycling to the entrance of pipe coil 2 through line 24 which connects the upper portion of separator 4 with fractionator 5. A portion of the residual oil withdrawn through line 23 may be diverted through line 45, cooled by passage through cooler 46, and admixed with the cracked products in line 21, a pump 47 being provided in line 45. Fractionator 5 is operated under conditions of temperature and pressure suitable to effect condensation and separation from the vapors of constituents too high boiling for inclusion in the motor fuel product. A pressure equal to or lower than that of separator 4 may be employed, valve 26 in line 24 being provided for any desired reduction in pressure. The liquid condensate in fractionator 5 is collected in the bottom and may be withdrawn therefrom through line 27. Any desired proportion of the liquid condensate thus obtained may be recycled to the entrance of pipe coil 2 by means of line 28 which connects line 27 with line 10.

The uncondensed vapors pass overhead from fractionator 5 through line 29 to a cooler 30 in which condensation of the motor-fuel constituents is effected. Cooling of the vapors may be assisted by passage thereof through heat exchanger 48 in indirect heat exchange with fresh feed to the system. The resulting mixture of liquids and gases passes from cooler 30 through line 31 to collector 6 in which separation of liquids and gases is effected. The gases may be withdrawn from collector 6 through line 32. The liquid condensate is withdrawn from collector 6 through line 33. A portion of the liquid condensate from collector 6 may be returned to fractionator 5 as reflux through line 34 which is provided with a pump 35 and connects line 33 with the upper portion of fractionator 5.

Instead of or in addition to the introduction to the system of a clean distillate oil as fresh feed through line 10 hydrocarbon oil of this nature may be introduced into the system through line 59 which is provided with a pump 60 and connects with absorber 61 wherein the hydrocarbon oil is passed in intimate contact with gases introduced into absorber 61 from collector 6 through line 32. The operation of absorber 61 is maintained to effect absorption by the hydrocarbon oil of the heavier constituents of the gases passing therethrough. The dry gases remaining are withdrawn from absorber 61 through line 62. The enriched hydrocarbon oil is withdrawn from the lower portion of absorber 61 through line 63, passes through heat exchanger 48, vapor heat exchanger 64 and is combined with the cycle gas oil passing to coil 2a through line 28. By this means convertible constituents in the gases from collector 6 such as heavier normally gaseous hydrocarbons susceptible to conversion to liquids may be recovered and returned to the system. This operation is advantageous where it is desired to admix with the oil passing to the inlet of coil 2a convertible gaseous hydrocarbons to be converted to liquid products during the cracking treatment.

Gases suitable for such gas reversion treatment also may be obtained from the stabilization treatment of the gasoline. The condensate passing through line 33 is transferred by means of pump 65 to gasoline stabilizer 66 in which conditions of temperature and pressure are maintained to effect stripping from the condensate of gaseous hydrocarbons undesired in the gasoline product which is withdrawn therefrom through line 67. Uncondensed gases are withdrawn overhead through line 68, are cooled in cooler 69 to effect condensation thereof, and the condensate is introduced into collector 70 in which any uncondensed gases are separated and withdrawn through line 71. The liquefied normally gaseous hydrocarbons are withdrawn from collector 70 through line 72 provided with pump 73 and passed to admixture with the cycle gas oil passing through line 28 to the inlet of coil 2a. If desired a portion of the liquefied gases may be diverted from line 72 through line 74 for return to the upper portion of stabilizer 66 as reflux liquid. Gas reversion is particularly advantageous in connection with the operation of this invention in that it facilitates separation in separator 3 and in that the presence of recirculated gas in the clean oil section of coil 2a and in coil 2b materially assists in polymerizing unsaturated constituents into gasoline.

Instead of, or in addition to, the introduction to the system of a clean distillate oil as fresh feed through line 10 or line 59 hydrocarbon oil of this nature may be introduced into the system through line 36 which is provided with a pump 37 and connects with fractionator 5. The hydrocarbon oil thus introduced into fractionator 5 serves as cooling medium to assist fractionation therein and is stripped of any gasoline constituents contained therein. The remaining unvaporized portion, together with condensate from the vapors introduced into line 24, is withdrawn through line 27 as described and passed to the entrance of pipe coil 2 through line 28.

Separator 4 may be employed to effect the preliminary treatment of a heavy or residual oil introduced to the system as fresh feed by removal therefrom of constituents suitable for recycling to the entrance of pipe coil 2 or suitable for inclusion in the motor fuel product. Furthermore, separator 4 may be employed to effect a cracking or a viscosity breaking of such heavy oil. Heavy oil, such as heavy gas oil, crude oil or a reduced crude may be introduced into separator 4 through line 38 provided with a pump 39. This oil may be preheated suitably to effect any desired cooling of the products of cracking in separator 4. In separator 4 the heavy oil thus introduced is intimately admixed with the products of cracking introduced through line 21 to effect distillation and any desired cracking or viscosity breaking of the heavy oil. The unvaporized residue from the heavy oil introduced through line 38 and residue from the cracked products introduced through line 21 are withdrawn through line 23. When it is desired to subject the residual oil thus collected in separator 4 to further cracking it may be introduced into section 2a of pipe coil 2 through line 12 or may be introduced into separator 3 through line 19. In this event the operating conditions of separator 4 may be maintained to effect the inclusion of any desired proportion of the heavy oil and cracked products in the residue thus collected. Line 40 connecting line 23 with line 19 is provided for the passage of any desired proportion 75

of this heavy oil to separator 3. Line 41 connecting line 23 with line 12 is provided to effect passage of any desired proportion of the residual oil from separator 4 into an intermediate point or points of section 2a of the pipe coil.

- In most cases it is desirable to carry on the cracking reaction with respect to the residual constituents of the crude oil in a once-through manner and avoid recirculating residual products 10 of cracking to the cracking zone. An advantageous operation in accordance with the invention is to introduce the topped or reduced crude into a primary dephlegmating or fractionating zone interposed between the zone of separation of cracked products, from line 21, and the fractionator 5 in which the separated vapors from the cracked products are given a primary dephlegmation or fractionation and the bottoms from this primary fractionation are employed as 15 stock that is introduced either at 12 to the cracking coil 2a or as the stock introduced at 19 into the separator 3.

To provide for this operation, separator 4 may be equipped with a trap-out tray 42, to provide 20 a primary fractionating or dephlegmating zone 4a in the upper portion thereof, from which condensate and unvaporized charge material from line 38 may be withdrawn separately through line 43 which connects with line 41, 25 whereby this liquid may be introduced to the cracking coil at 12. Branch line 44 connects lines 43 and 40 whereby this liquid may be introduced into separator 3 at 19. The vapors from this primary fractionating zone 4a pass to the fractionator 5, the clean condensate from which is cycled through line 28 to the cracking coil 2 as 30 has been explained.

Although the separator 4 may be employed as a low pressure evaporator, with relatively small 40 amounts of cracking being carried on therein, an advantageous operation, in accordance with the invention, is to maintain conditions of temperature and pressure adequate to carry on extensive cracking therein. In the latter operation, the 45 cracking may, in accordance with the invention, be restricted with respect to the liquid components by withdrawing the liquid separating out at such a rate as to prevent the accumulation of liquid in the separating chamber.

With the introduction of a heavy oil into separator 4 the low-boiling constituents thereof pass overhead through line 24 into fractionator 5 wherein they are separated in the manner described into a condensate suitable for charging 50 stock and a vapor fraction containing motor-fuel constituents. Fractionator 5 may be provided with suitable trays or bubble caps or other gas and liquid contact means for promoting the condensation, absorption, stripping and evaporation 55 incidental to the desired fractionation.

In an example of the invention, clean condensate stock is subjected to cracking in the heating coil 2a at a temperature of 1000° F. Reduced crude preheated to a temperature of 650° F. is introduced into the intermediate separator 3. The liquid separating out in chamber 3 is rapidly withdrawn through line 16 and the separated vapors, at a temperature of 800° F., pass to the 60 cracking coil 2a in which the vapors are subjected to cracking at a temperature of 950° F. Cracking is continued in the separator 4, which is maintained at 400 pounds pressure and at a temperature of 850° F., the residual constituents 65 of cracking being withdrawn at a rate adequate

to prevent the accumulation of liquid in the separator.

In another example of the invention clean distillate stock is subjected to cracking at a temperature of 1000° F. in cracking coil 2a and reduced crude which has been preheated to a temperature of 750° F. is introduced through line 12 and the commingled products are subjected to cracking at a temperature of 900° F. in the latter portion of the coil 2a. Vapors at a temperature of 825° F. pass from the intermediate separator 3 to the cracking coil 2b in which the vapors are subjected to cracking at a temperature of 950° F. The cracking is continued in the separator 4 under 400 pounds pressure at a temperature of 850° F., the residual products of cracking being withdrawn so as to prevent the accumulation of liquid in the separator.

The invention has been described with reference to a specific embodiment thereof, but it is to be understood that this is not limited by such specific reference but is capable of other embodiments which may be beyond the physical limitations of the apparatus illustrated.

I claim:

1. The method of cracking hydrocarbon oil that comprises passing a stream of hydrocarbon oil under superatmospheric pressure through primary and secondary sections of an elongated heating zone of restricted cross section, applying heat to said primary section of the elongated heating zone to subject the stream of oil flowing therein to cracking temperature and effect substantial cracking, introducing oil formed as hereinafter specified into the secondary section of the elongated heating zone so that the resultant mixture of said oil and the products from the primary section of the elongated heating zone constitutes the stream flowing in the secondary section thereof, applying heat to said secondary section of the elongated heating zone to subject the stream flowing therein to cracking temperature and continue the cracking, delivering the resultant cracked products from the secondary section of the elongated heating zone to an enlarged separating zone maintained under superatmospheric pressure wherein separation of vapors from residue takes place, passing the separated vapors to a second elongated heating zone of restricted cross section wherein the vapors are heated and subjected to vapor phase cracking, directing the resultant cracked products into a second enlarged separating zone wherein separation of vapors from residue takes place, passing the separated vapors from the second enlarged separating zone to a primary fractionating zone, withdrawing residue from the first enlarged separating zone and subjecting it to flash distillation under reduced pressure to produce a flashed condensate, introducing resultant flashed condensate into the primary fractionating zone wherein fractionation takes place to separate uncondensed vapors from a fraction comprising reflux condensate and unvaporized constituents of the introduced flashed condensate, conducting said fraction comprising reflux condensate and unvaporized constituents of the flashed condensate from the primary fractionating zone as the aforesaid oil introduced into the secondary section of the first elongated heating zone, subjecting separated vapors from the primary fractionating zone to further fractionation to separate a reflux condensate from lighter products and cycling said reflux condensate to the primary section of the first elongated heating zone.

2. The method of cracking hydrocarbon oil that comprises passing a stream of hydrocarbon oil under superatmospheric pressure through primary and secondary sections of an elongated heating zone of restricted cross section, applying heat to said primary section of the elongated heating zone to subject the stream of oil flowing therein to cracking temperature and effect substantial cracking, introducing oil formed as hereinafter specified into the secondary section of the elongated heating zone so that the resultant mixture of said oil and the products from the primary section of the elongated heating zone constitutes the stream flowing in the secondary section thereof, applying heat to said secondary section of the elongated heating zone to subject the stream flowing therein to cracking temperature and continue the cracking, delivering the resultant cracked products from the secondary section of the elongated heating zone to an enlarged separating zone maintained under superatmospheric pressure wherein separation of vapors from residue takes place, passing the separated vapors to a second elongated heating zone of restricted cross section wherein the vapors are heated and subjected to vapor phase cracking, directing the resultant cracked products into a second enlarged separating zone wherein separation of vapors from residue takes place, passing separated vapors from the second enlarged separating zone to a primary fractionating zone, withdrawing residue from the first enlarged separating zone and subjecting it to flash distillation under reduced pressure to produce a flashed condensate, introducing resultant flashed condensate and charging stock into the primary fractionating zone wherein fractionation takes place to separate uncondensed vapors from a fraction comprising a mixture of reflux condensate and unvaporized constituents of the introduced flashed condensate and charging stock, conducting said mixture from the primary fractionating zone as the aforesaid oil introduced into the secondary section of the elongated section of the heating zone, subjecting separated vapors from the primary fractionating zone to further fractionation to separate a reflux condensate from lighter products and cycling said reflux condensate to the primary section of the first elongated heating zone.

3. The method of cracking hydrocarbon oil that comprises passing a stream of hydrocarbon oil under superatmospheric pressure through primary and secondary sections of an elongated heating zone of restricted cross section, applying heat to said primary section of the elongated heating zone to subject the stream of oil flowing therein to cracking temperature and effect substantial cracking, introducing oil formed as hereinafter specified into the secondary section of the elongated heating zone so that the resultant mixture of said oil and the products from the primary section of the elongated heating zone constitutes the stream flowing in the secondary section thereof, applying heat to said secondary section of the elongated heating zone to subject the stream flowing therein to cracking temperature and continue the cracking, delivering the resultant cracked products from the secondary section of the elongated heating zone to an enlarged separating zone maintained under superatmospheric pressure wherein separation of vapors from residue takes place, passing the separated vapors to a second elongated heating zone of restricted cross section wherein the vapors are heated and subjected to vapor phase cracking, directing the resultant cracked products into a second enlarged separating zone wherein separation of vapors from residue takes place, passing separated vapors from the second enlarged separating zone to a primary fractionating zone, introduced charging stock comprising residual constituents of crude petroleum into said primary fractionating zone wherein fractionation takes place to separate uncondensed vapors from a fraction comprising reflux condensate and unvaporized constituents of the introduced charging stock, conducting said fraction comprising reflux condensate and unvaporized constituents of the charging stock from the primary fractionating zone as the aforesaid oil introduced into the secondary section of the first elongated heating zone, subjecting separated vapors from the primary fractionating zone to further fractionation to separate a reflux condensate from lighter products and cycling said reflux condensate to the primary section of the first elongated heating zone.

4. The method of cracking hydrocarbon oil that comprises passing a stream of hydrocarbon oil under superatmospheric pressure through primary and secondary sections of an elongated heating zone of restricted cross section, applying heat to said primary section of the elongated heating zone to subject the stream of oil flowing therein to cracking temperature and effect substantial cracking, introducing oil formed as hereinafter specified into the secondary section of the elongated heating zone so that the resultant mixture of said oil and the products from the primary section of the elongated heating zone constitutes the stream flowing in the secondary section thereof applying heat to said secondary section of the elongated heating zone to subject the stream flowing therein to cracking temperature and continue the cracking, delivering the resultant cracked products from the secondary section of the elongated heating zone to an enlarged separating zone maintained under superatmospheric pressure wherein separation of vapors from residue takes place, passing the separated vapors to a second elongated heating zone of restricted cross section wherein the vapors are heated and subjected to vapor phase cracking, directing the resultant cracked products into a second enlarged separating zone wherein separation of vapors from residue takes place, passing separated vapors from the second enlarged separating zone to a primary fractionating zone, introduced charging stock comprising residual constituents of crude petroleum into said primary fractionating zone wherein fractionation takes place to separate uncondensed vapors from a fraction comprising reflux condensate and unvaporized constituents of the introduced charging stock, conducting said fraction comprising reflux condensate and unvaporized constituents of the charging stock from the primary fractionating zone as the aforesaid oil introduced into the secondary section of the first elongated heating zone, subjecting separated vapors from the primary fractionating zone to further fractionation to separate a reflux condensate from lighter products and cycling said reflux condensate to the primary section of the first elongated heating zone.

5. The method of cracking hydrocarbon oil that comprises passing a stream of hydrocarbon oil under superatmospheric pressure through primary and secondary sections of an elongated heating zone of restricted cross section, applying heat to said primary section of the elongated heating zone to subject the stream of oil flowing therein to cracking temperature and effect substantial cracking, introducing oil formed as hereinafter specified into the secondary section of the elongated heating zone so that the resultant mixture of said oil and the products from the primary section of the elongated heating zone constitutes the stream flowing in the secondary section thereof, applying heat to said secondary section of the elongated heating zone to subject the stream flowing therein to cracking temperature and continue the cracking, delivering the resultant cracked products from the secondary section of the elongated heating zone to an enlarged separating zone maintained under superatmospheric pressure wherein separation of vapors from residue takes place, passing the separated vapors to a second elongated heating zone of restricted cross section wherein the vapors are heated and subjected to vapor phase cracking, directing the resultant cracked products into a second enlarged separating zone wherein separation of vapors from residue takes place,

passing separated vapors from the second enlarged separating zone to a primary fractionating zone, introducing charging stock comprising residual constituents of crude petroleum into said primary fractionating zone wherein fractionation takes place to separate uncondensed vapors from a fraction comprising reflux condensate and unvaporized constituents of the introduced charging stock, conducting said fraction comprising reflux condensate and unvaporized constituents of the charging stock from the primary fractionating zone as the aforesaid oil introduced into the secondary section of the first elongated heating zone, passing separated vapors from the primary fractionating zone to a secondary fractionating zone wherein the vapors are fractionated to separate a reflux condensate from vapors and gases, cycling said reflux condensate to the primary section of the first elongated heating zone, subjecting the separated vapors and gases from the secondary fractionating zone to further fractionation to form distillate and lighter and heavier fractions comprising normally gaseous constituents and directing the heavier fraction comprising normally gaseous constituents to the primary section of the first elongated heating zone.

RICHARD F. TROW.
